(57) **CLAIM**

The ornamental design for a personal portable air purifier, as shown and described.

DESCRIPTION

FIG. 1 is a perspective view of a personal portable air purifier design showing my new design.

FIG. 2 is a front view of a personal portable air purifier.

FIG. 3 is a rear view of a personal portable air purifier.

FIG. 4 is a left side view of a personal portable air purifier.

FIG. 5 is a right side view of a personal portable air purifier.

FIG. 6 is a top view of a personal portable air purifier.

FIG. 7 is a bottom view of a personal portable air purifier; and,

FIG. 8 is a rear, left side perspective view of a personal portable air purifier.

Any shading and cross-hatching are not features of the design but are utilized to illustrate the surface contours of the personal portable air purifier design in the drawings.

The AVIAIR forming part of the claimed design is a registered trademark of SHU-HSIEN CHOU, BELLSON.

The broken lines shown in the figures are for the purpose of illustrating portions of the personal portable air purifier and form no part of the claimed design.
